Primary Examiner — Cathron C Brooks*Assistant Examiner* — Sharon S Oum(74) *Attorney, Agent, or Firm* — McGarry Bair PC(57) **CLAIM**

The ornamental design for a canopy for a ceiling fan, as shown and described.

DESCRIPTION

FIG. 1 is a bottom perspective view of a canopy for a ceiling fan;

FIG. 2 is a top perspective view thereof, but shown without the ceiling fan environment;

FIG. 3 is a bottom view thereof;

FIG. 4 is a front side view thereof, with rear, right, and left side views being mirror images thereof; and,

FIG. 5 is a top view thereof.

The broken lines illustrate environmental structure and form no part of the claimed design.

1 Claim, 3 Drawing Sheets(56)
